Primary Examiner—Louis S. Zarfas**Assistant Examiner**—Robert A. Delehanty**Attorney, Agent, or Firm**—John K. Park; Park & Sutton LLP**[57] CLAIM**

The ornamental design for a golf club divider for a golf bag, as shown and described.

DESCRIPTION

FIG. 1 is a top perspective view of a golf bag divider for a golf bag showing my new design in use;

FIG. 2 is a top perspective view enlarged to show details thereof;

FIG. 3 is a top plan view thereof;

FIG. 4 is a front elevational view thereof;

FIG. 5 is a side elevational view thereof; and,

FIG. 6 is a rear elevational view thereof.

The broken lines showing of a portion of a golf bag are for illustration purpose only and forms no part of the claimed design.
